Term of patent 3½ years

(Cl. D34—2)

FIG. 1 is a front perspective view of a plush dog toy showing my new design.

FIG. 2 is a rear perspective view thereof.

The characteristic features of my design reside in the combination of the horizontal angular ears with droopy moustache and inverted tear-shaped eyes, all as shown.

I claim:

The ornamental design for a plush dog toy, as shown and described.
